DISPLAY RACK

Shulman A. Moog, St. Louis, Mo., assignor to St. Louis Spring Company, St. Louis, Mo., a corporation of Missouri

Application September 10, 1932
Serial No. 632,590

2 Claims. (Cl. 211—182)

This invention relates generally to display racks and has more particular reference to a rack especially adapted for the display of bar material, such as, for instance, automotive spring-leaves and the like.

My invention has for its prime object the provision of a sturdy, durable, and readily manufactured skeleton or open rack for the efficient storage and display in tiers or superposed rows of spring-leaves and other bar articles of different lengths, the rack including article-intervening members spaced the one from the other for maintaining the articles in the several tiers or rows in orderly stacks or columns for convenient individual accessibility.

And with the above and other objects in view, my invention resides in the novel features of form, construction, arrangement, and combination of parts hereinafter described and pointed out in the claims.

In the accompanying drawing,—

Figure 1 is a front elevational view of a spring-leave display-rack embodying my invention;

Figure 2 is a side elevational view of the rack; Figure 3 is a fragmental sectional view of the rack taken approximately on the line 3—3, Figure 2; and

Figure 4 is a detail sectional view of the rack taken approximately on the line 4—4, Figure 1.

Referring now more in detail and by reference characters to the drawing, which illustrates a preferred embodiment of my invention, the rack includes an open or so-called skeleton front or main frame A of any suitable height, which comprises suitably spaced corner posts or standards 1, 1, suitably connected or tied together in parallel relation by a top cross-member 2 and a series of lower cross or tier-members 3 disposed in suitably spaced relation one from the other and from the top-member 2. The upstanding members or posts 1, 1, are preferably in the form of flat strips provided at their respective lower ends with outwardly flanged extensions 4 forming feet adapted for securing or attachment to a floor or other support. The cross-members 2, 3, are also preferably in the form of flat strips laterally flanged at their opposite ends for convenient bolting or other rigid connection with the posts 1, as shown.

B designates the lower sub or rear open skeleton frame of the rack, which is of the same width as the frame A and is in like manner constructed of corner-posts 5 and cross top and tier post-connecting members 6, 7, respectively, the posts 5 similarly having feet 8 for securing to the floor or other support. However, as best seen

in Figure 2, the frame B is of greatly reduced height relatively to the height of rack A and its posts 5 are rigidly connected or tied in aligning parallel relation to the posts 1 by straps 9, suitably bolted or otherwise fixed to the posts 1, 5, as best seen in Figure 2, the posts 1, 5, being preferably braced adjacent their lower end by an additional cross-strap 10.

C, D, and E designate respective additional open skeleton sub or rear frames of the rack, which, except as presently stated, are substantially of like structure, and each of which, substantially similar to the frame B, is constructed of end upright members or strips 11 and cross top and tier strip-connecting members 12, 13, respectively. In the present rack, the uppermost frame or unit E is of also reduced height relatively to the under sub-frames B, C, and D and is without an intermediate or tier cross-member 13.

However, while the several sub-frames are substantially or generally structurally similar, the frame C is disposed at less distance rearwardly from the frame A than is the frame B and at or adjacent the upper end of its upright members 11 is rigidly tied to the frame A by preferably horizontally disposed straps 14 of reduced length relatively to the straps 9, the upright end-members 11 of frame C being rigidly fixed at their lower end to the straps 9, as best seen in Figure 2.

Similarly the frames D and E are disposed successively at lesser distances rearwardly from the frame A and at or adjacent the upper end of their respective upright end-members 11 are rigidly tied to the frame A by respective horizontally disposed straps 15, 16, successively also of reduced length and also of reduced length relatively to the straps 14, the uprights 11 of the frame D being bolted or otherwise fixed at their lower end to the straps 14, and the uprights 11 of the upper frames E being bolted or otherwise fixed at their lower end to the straps 15, all as best seen in Figure 2.

In such manner, the respective rear or sub frames B, C, D, and E are not only rigidly tied one to the other, but also rigidly tied in superposed so-called stepped formation and in parallel relation to the front or main frame A. The several sub frames B, C, D, and E may also vary in height relatively to one another, and the rack may include a greater or lesser number of such sub or rear frames as may be necessary to meet the requirements of any particular installation. The combined height of the several sub-frames, however, substantially equals the height of the main frame A, and in the finished rack the respective

intermediate cross top and tier members 12, 13, of the sub or rear frames are disposed in the respective horizontal planes of, or in horizontal registration with, the lower cross-members 3 of frame A and the top cross member 12 of the uppermost sub frame E is preferably in the horizontal plane of, or in horizontal registration with, the top cross member 2 of the main or front frame A.

10 Thus the rack is of stepped formation well adapted for the support by its respective cross-members of bar members, such as spring-leaves or the like F, of correspondingly different lengths, and for segregating or separating the displayed articles F, a requisite number of vertically disposed rods 17 is inserted preferably downwardly each through a particular series of vertically registering apertures provided for the purpose in the series of superposed cross-members 2, 3, of the main frame A. In like manner, each of the rear or sub frames B, C, D, and E is provided with a series of article-segregating rods 18 disposed vertically in spaced registering relation with the rods 17.

25 Thus the several cross-members of the rack are correspondingly intersected, each pair of adjacent rods 17 providing between the respective pairs of superposed tier-members 3 an article-receptive approximately rectangular frame-opening 19, in and through which the articles F to be displayed may be endwise inserted for residing on the lower tier-member of the pair, the frame-openings 19 in the frame A being horizontally aligned with similarly formed frame-openings in the rear or sub frames B, C, D, and E.

30 Most of the rods 17, 18, are provided at their respective upper end with a head 20 for engaging the upper face of the top cross-member of the particular frame for suspending such rods 17 or 18 removably therefrom, and a suitable retainer-plate 21 is mounted over the series of rod-heads 20 residing on the particular cross-member for preventing dislodgement of said rods 17, 18, from the respective frames. Some of the rods 17, 18, 45 however, are threaded at their upper end, as at t, and provided with a jam-nut 22 normally underlying said frame top cross-member. Such threaded rods extend upwardly through the respective plates 21 and such respective retainer-plates 21 50 are, in turn, preferably detachably engaged with the specific frame-members by means of suitable fastening nuts 23 threaded on such projecting rods, as shown. Of course, it will be understood that such threaded rods 17, 18, are equipped with the nuts 22 and the frame upper cross-members 55 suitably fitted thereover in the assembling of the rack.

60 The spacing between the rods 17, 18, may be readily changed by varying the spacing of their accommodating apertures provided in the several cross-members of the rack, or by omitting one or more of the rods 17, 18, for reception of bar articles or the like of various widths in the so formed frame-openings, and it will be evident 65 that said articles may, most conveniently for increasing the storage capacity of the rack, be stacked or piled one upon another in the frame-openings 19, the rods 17, 18, then most effectively providing a lateral support for the stack of articles

70 F, as illustrated in Figure 3.

The several members of the rack are constructed of metal or other preferably unbreakable material, and I thus provide a most convenient, economical, sturdy, durable, and highly useful rack for compactly displaying relatively awkward and bulky bar-articles of different lengths, as automotive leaf-springs and the like, the rack being also readily collapsed or disassembled to so-called "knocked-down" condition for convenient handling and shipping. The displayed articles are readily visible from all sides thereof and may with ease, facility, and convenience be removed from or replaced in the rack one by one without interfering with or disturbing the other articles in the rack, each cross-member 2, 3, of the main frame being preferably provided with a registering flange strip 24 providing a way for the convenient insertion and support of descriptive matter (not shown) pertaining to the displayed articles.

80 It will be understood that minor changes and modifications in the form, construction, arrangement, and combination of the several parts of the rack may be made and substituted for those herein shown and described without departing 85 from the nature and principle of my invention.

Having thus described my invention, what I claim and desire to secure by Letters Patent, is,—

1. A display-rack including an upstanding main-frame, a plurality of upstanding sub-frames, said main and sub-frames each comprising a pair of corner-posts and a plurality of vertically spaced cross-members fixed at their respective ends to the posts for rigidly tying the same together in spaced parallel relation, and a plurality of pairs of straps of different lengths for rigidly tying the sub-frames to and upon one side of the main frame in stepped formation and parallel relation, the corner-posts of each respective upper sub-frame being rigidly fixed at their lower end to the tying-straps of the next adjacent lower sub-frame and cross-members and posts of the respective sub-frames being in registration with respective cross-members and posts of the main frame for forming rows of vertically stepped bar-article accommodating seats.

105 2. A display-rack including an upstanding main-frame, a plurality of upstanding sub-frames, said main and sub-frames each comprising a pair of corner-posts and a plurality of vertically spaced cross-members fixed at their respective ends to the posts for rigidly tying the same together in spaced parallel relation, a plurality of pairs of straps of different lengths for rigidly tying the sub-frames to and upon one side of the main frame in stepped formation and parallel relation, the corner-posts of each respective upper sub-frame being rigidly fixed at their lower end to the tying-straps of the next adjacent lower sub-frame and cross-members and posts of the respective sub-frames being in registration with respective cross-members and posts of the main frame for forming rows of vertically stepped bar-article accommodating seats, and a series of spaced registering bars intersecting and engaging with the cross-members of the respective frames for separating the displayed articles.
